UNITED STATES PATENT OFFICE.

ARNOLD KROHN, OF EAST WEYMOUTH, MASSACHUSETTS, ASSIGNOR TO THE REECE
BUTTON HOLE MACHINE COMPANY, OF BOSTON, MASSACHUSETTS, A CORPORATION
OF MAINE.

THREAD RETAINER FOR SEWING MACHINES.

Application filed March 2, 1926. Serial No. 91,721.

This invention relates to two-thread sewing machines of the type in which the under-thread manipulating mechanism includes a needle carried by an oscillatory needle carrier and one of the objects of the invention is to provide a novel device for preventing the under needle from becoming de-threaded either when the sewing machine is brought to rest and the thread is trimmed or severed, or during the formation of the first stitch when the sewing operation is begun.

The invention includes a thread-holding member which is associated with the oscillatory needle carrier for the under needle and is arranged to grip the thread lightly at a point between the thread-guiding eye that is carried by the needle carrier and the eye of the needle, the grip on the thread being sufficient to prevent the thread from being accidentally withdrawn from the eye of the needle but not being sufficient to increase materially the tension on the thread during the sewing operation.

In order to give an understanding of the invention I have illustrated in the drawings a selected embodiment thereof which will now be described after which the novel features will be pointed out in the appended claims.

Fig. 1 is a view of the turret of a button-hole sewing machine carrying the under-thread manipulating mechanism and having my improvements applied thereto;

Fig. 2 is an enlarged view of the needle carrier with the improved thread-gripping device thereof;

Fig. 3 is a side view of the needle carrier;

Fig. 4 is a section on the line 4—4, Fig. 2;

Fig. 5 is a section on the line 5—5, Fig. 2.

The invention is herein illustrated as it might be applied to a sewing machine of the general type shown in Patent No. 1,188,942, dated June 27th, 1916 but as the invention relates simply to the device associated with the under-thread manipulating mechanism for preventing the de-threading of the under needle I have not thought it necessary to illustrate the complete sewing machine herein.

In a sewing machine of the type illustrated in said patent the under-thread manipulating mechanism, which includes an oscillatory curved needle, is carried by a turret which is situated beneath the work and is rotatably mounted on the frame of the

sewing machine. Such turret is indicated generally at 1. The under needle which constitutes part of the means for manipulating the under thread is indicated at 2, this being a curved needle which is mounted in 60 an oscillatory needle carrier 3. This needle carrier is formed with a depending arm 4 carried by a horizontal rock shaft 5 which is journaled in the turret and which is oscillated by any suitable or usual means thereby to cause the needle to move upwardly through the throat plate 6 and through the work and then to be retracted into the position shown in Fig. 1.

7 indicates the usual oscillatory looper 70 which co-operates with the upper and under needle to assist in concatenating the upper and under threads. The under thread which is indicated at 8 is led in usual way through a hollow spindle 9 of the turret and thence out through the opening 10 and through the tension 11 and thence through guide eyes 12 and 13 carried by a thread-guiding arm 14 and thence through a guide eye 15 carried by the arm 4 of 80 the needle carrier and thence through another guide eye 16 formed in the needle carrier, said thread extending from the guide eye 16 to the eyes 17, 18 of the under needle. 85

The parts thus far described are or may be all as substantially shown in Patents No. 1,188,942 or No. 1,535,399, April 28th, 1925, and as the operation of a sewing machine of this type is well known to those skilled in the art it will not be necessary to further illustrate these parts. 90

In the operation of sewing machines of this type it sometimes happens that the under needle 2 will become de-threaded either when the machine is brought to rest and the threads are trimmed by some suitable thread-trimming mechanism or when the machine is first started, and to prevent this occurrence I have provided herein a novel device which applies a light tension to the thread between the guide eye 16 on the needle carrier and the needle eye 17, this tension being sufficient to prevent the thread from being pulled backwardly through the needle eye thus causing the de-threading of 100 the needle. 105

The device herein shown for this purpose is in the form of a finger 19 which is yieldingly held against the thread 8 as it emerges from the guide eye 16. This finger forms 110

part of a resilient arm 20 which overlies the outer face 21 of the needle carrier, said finger 19 extending across the end of the needle carrier as shown best in Figs. 2 and 5. The end of the needle carrier is illustrated as provided with a recess 22 in which the finger 19 is received so that said finger does not extend beyond the end of the needle carrier. The resiliency of the arm 20 10 lightly presses the finger 19 against the wall 23 of the groove 22. The under thread 8 passes behind the finger 19 and is thus lightly pressed against the wall by the arm, said arm applying sufficient tension to the 15 thread to prevent it being pulled back through the eye of the needle 2.

The device can be conveniently made from a piece of resilient wire which is bent into the shape shown to present the resilient arm 20 and the finger 19. Said device is shown as being retained in place by means of a screw 24, the end of the arm 20 passing under the head of the screw and being clamped against the face of the needle carrier by said screw head. The needle carrier is preferably formed with a groove 25 to receive the arm. The end of the finger 19 extends slightly beyond the inner face 26 of the needle carrier and is bent downwardly as shown at 27, the purpose of which construction is to facilitate the placing of the thread under the finger 19 when the machine is threaded up. The threading up of the machine involves the insertion of 30 the thread through the guide eyes 12, 13, 15 and 16 in succession. As the thread is inserted through the eye 16 it will emerge from the eye on the outside of the finger 19 since the latter is yieldingly pressed against the wall 23 by the arm 20 and to place the thread back of the finger 19 and in a position to be gripped thereby the operator 35 passes the thread around the beak or nose

27 and then pulls backwardly, the thread being thus drawn under the finger 19 and 45 into the position shown in Figs. 2 and 4. The thread is then threaded through the eyes 17, 18 of the needle 2 thus completing the threading of the device.

The pressure which the finger 19 applies 50 on the thread 8 is relatively light but is sufficient to prevent the needle from becoming de-threaded.

While I have illustrated herein a selected embodiment of the invention I do not wish 55 to be limited to the constructional details shown.

I claim—

1. In a sewing machine, the combination with an oscillatory needle carrier having a 60 thread-guiding eye through which the under thread passes, of a needle carried by said carrier and also having an eye through which said thread passes, and means for applying a light tension to said thread between the eye of the needle carrier and the eye of the needle. 65

2. In a sewing machine, the combination with an oscillatory needle carrier having a 70 thread-guiding eye through which the under thread passes, of a needle carried by said carrier and also having an eye through which said thread passes, and a finger bearing on the thread between the eye of the needle carrier and the eye of the needle. 75

3. In a sewing machine, the combination with a needle carrier, of a needle extending from the end thereof, said needle carrier having a thread-guiding eye extending therethrough and terminating at said end adjacent the base of the needle, and a finger yieldingly held against the thread at the delivery end of said eye. 80

In testimony whereof, I have signed my name to this specification.

ARNOLD KROHN.
